US00D647540S

(12) **United States Design Patent**
Drenth

(10) **Patent No.:** **US D647,540 S**
(45) **Date of Patent:** ** *Oct. 25, 2011

(54) **CORE BARREL SLEEVE WITH AXIAL GROOVES**

(75) Inventor: **Christopher L. Drenth**, Draper, UT (US)

(73) Assignee: **Longyear TM, Inc.**, South Jordan, UT (US)

(**) Term: **14 Years**

(21) Appl. No.: **29/383,623**

(22) Filed: **Jan. 20, 2011**

CLAIM

The ornamental design for a core barrel sleeve with axial grooves, as shown and described.

DESCRIPTION

FIG. 1 is a front elevational view of a core barrel sleeve with axial grooves showing my new design as used in a core barrel assembly;

FIG. 2 is an enlarged exploded perspective view thereof; FIG. 3 is an enlarged assembled front elevational view thereof;

FIG. 4 is a right elevational view thereof;

FIG. 5 is a back elevational view thereof;

FIG. 6 is a left elevational view thereof;

FIG. 7 is a top plan view thereof; and,

FIG. 8 is a bottom plan view thereof.

The broken lines showing environment in the drawings are included for illustrative purposes only and form no part of the claimed design.
